(21) Appl. No.: **29/228,738**

(57) **CLAIM**

(22) Filed: **Apr. 28, 2005**

The ornamental design for a sorter for an image data recorder for medical use, as shown and described.

(30) **Foreign Application Priority Data**

Nov. 8, 2004 (JP) 2004-034027

DESCRIPTION

(51) **LOC (8) Cl.** **24-01**

FIG. 1 is a top, front and side perspective view of a sorter for an image data recorder for medical use, showing my new design;

(52) **U.S. Cl.** **D24/158**

FIG. 2 is a front elevational view thereof;

(58) **Field of Classification Search** D24/158-161;
378/167, 171, 172, 181-183; 396/512, 517;
271/292, 299; D16/246, 247; D18/38, 39,
D18/47, 49

FIG. 3 is a rear elevational view thereof;

See application file for complete search history.

FIG. 4 is a top plan view thereof;

FIG. 5 is a bottom plan view thereof;

FIG. 6 is a side elevational view thereof from the right of FIG. 2;

FIG. 7 is a side elevational view thereof from the left of FIG. 2; and,

FIG. 8 is a perspective view thereof, with the broken line showing of the image data recorder being for illustrative purposes only and forming no part of the claimed design.
